DESIGN FOR A SIGN EXHIBITOR

Herbert S. Taylor, Los Angeles, Calif.

Application April 4, 1946, Serial No. 128,290

Term of patent 3½ years

(Cl. D1—12)

To all whom it may concern:

Be it known that I, Herbert S. Taylor, a citizen of the United States, residing at Los Angeles, in the county of Los Angeles and State of California, have invented a new, original, and ornamental Design for Sign Exhibitor, of which the following is a specification, reference being had to the accompanying drawing, forming part thereof.

Figure 1 is a perspective view of a sign exhibitor, showing my new design.

Figure 2 is a top plan view thereof.

I claim:

The ornamental design for a sign exhibitor, as shown.

HERBERT S. TAYLOR.
